PREFABRICATED REFRIGERATOR
CONSTRUCTION

Frederick M. Jones, Minneapolis, Minn., assignor,
by mesne assignments, to U. S. Thermo Control
Co., Minneapolis, Minn., a corporation of
Minnesota

Application January 2, 1947, Serial No. 719,822

9 Claims. (Cl. 62—89)

1

My invention is related to an improvement in prefabricated refrigerator construction. In particular it is related to an improvement in a refrigerator which is formed of a plurality of prefabricated members that are adapted to be assembled into an enclosure at the place of use and which have been fabricated in such a manner as to provide superior insulating qualities.

The present invention is related to a form of refrigerator generally referred to as a "deep freeze" unit which has gained popularity as a means for storing perishable foods in such a manner that they will retain the qualities of fresh foods over long periods of time. Units of this type are generally located in an out of the way place in the dwelling such as the basement, or some area remote from the kitchen, for the reason they are generally of considerable size and are not frequently used. Because of its bulky dimensions and weight, a certain amount of difficulty may be encountered in moving such a unit into the basement or other remote area of the dwelling in a pre-assembled condition. Under these conditions it is both desirable and economical to provide the construction in the form of a knock-down assembly which may be moved into the basement as a number of prefabricated integral units and assembled at the point where it will more or less permanently remain. In a knock-down assembly it is desirable that the several elements of the assembly be constructed and adapted for joining to the remainder of the elements in a simplified manner and yet maintain the greatest possible efficiency in the insulating qualities of the assembled refrigerator. For this reason the refrigerator is composed of a plurality of separable wall members or panels formed of reinforced insulating material which have been metalclad and constructed in a manner so that they may be easily joined to each other. When in use, the temperature within the refrigerator will be considerably below that existing externally to its wall members and, therefore, precautions must be taken to prevent the metalclad walls from acting as conductors of heat through the wall members at their areas of junction with each other. To accomplish this, each of the wall members has a plurality of joining surfaces in the form of tongue and groove surfaces. Both the tongue and the groove surfaces are formed with a base of plywood which is less liable to warp and will prevent moisture from penetrating into the insulation material. A single strip of wood mounted on the center of one of the plywood strips forms a tongue surface and two strips of

2

wood fastened to the lateral edges of another plywood strip forms a groove surface. The metal-clad surfaces are formed in two pieces, one of which is intended to form the exterior surface, and the other the interior surface of the wall member. The two pieces of metal are separated from each other at the respective tongue and groove surfaces so that an area of low thermal transfer capacity in the form of wood and plywood separate the two metal pieces to prevent a continuous flow of heat through the metal walls of any one member. The fastening means which join any one wall member to another, passes through the two members at the area of low thermal conductivity without contacting either of the opposed metal surfaces so as to prevent temperature transfer through the fastening means. Furthermore, in order to render the area of junction substantially air-tight, a pair of resilient gaskets is interposed between each pair of wall members adjacent the tongue and groove surfaces. In this manner the several internal metal surfaces of the refrigerator are completely isolated from the external metal surfaces and the areas of junction are all rendered substantially air-tight.

An object of my invention is to provide a prefabricated refrigerator formed of a number of elements which are adapted for assembly at the point of use.

Another object is to provide a refrigerator assembly consisting of a plurality of preformed metalclad wall members each of which has at least one surface of material having a low thermal transfer capacity co-operable with a similar surface of another wall member in such a manner as to preclude thermal transfer at the junction of the metalclad wall members.

Another object is to provide a knock-down refrigerator assembly having a plurality of prefabricated wall elements adapted to be joined to be joined to one another to form an enclosure which will be cooled on its interior, in which each of the wall members has a plurality of surfaces adapted to be joined to co-operating surfaces of other wall members in such a manner as to preclude thermal transfer between the interior and exterior of the enclosure.

A further object is to provide a knock-down refrigerator assembly consisting of a plurality of wall members having co-operable tongue and groove surfaces, which members are adapted to be assembled into an enclosure by consecutively joining the several wall members to one another, together with a refrigerator unit consisting of a

plurality of heat exchanging shelves that are adapted to be mounted in the enclosure as it is nearing completion and connected to an exterior source of fluid refrigerant such as a compressor which may be positioned adjacent the assembly.

Other and further objects will be apparent from the following description and claims and from the several views of the invention in the appended drawings in which:

Fig. 1 is a front elevation of a prefabricated refrigerator which forms the present invention with a part of the front wall broken away to show the interior construction;

Fig. 2 is a side elevation taken from the right side of Fig. 1 with portions broken away to show the interior construction;

Fig. 3 is a plan view of the refrigerator with a portion of the top surface broken away;

Fig. 31 is a bottom plan view of the structure shown in Fig. 29; and

Fig. 32 is a cross-section taken on the lines 32—32 of Fig. 29.

General assembly

Referring now to Figs. 1—4, general reference numeral 50 indicates a prefabricated refrigerator assembly consisting of a base member 52, on which is mounted a front panel member 54, having a plurality of outwardly swinging door mem-

bers 56 that are hingedly mounted on panel member 54 by hinges 58 and releasably latched to the front panel member by latched mechanism indicated by the general reference numeral 60. An indicating thermometer 76 is positioned through an aperture 72 in the central portion of front panel member 54 for indicating the temperature within the interior of the refrigerator. Also mounted on base member 52 is a rear panel 74, a first end panel 76, and a second end panel 78. Mounted on top of the four panels which constitute the side walls of the refrigerator is a cover member or top panel 80. The several walls or panels of the assembly are secured to one another and to the base member 52 in a manner to be described in detail hereinafter by a plurality of bolts 82. Mounted within the enclosure are a plurality of heat exchanging shelves 84 which are supported on racks 85 and connected by conduits 86 and 88 to a pair of nipples 90 and 92 which are adapted to be connected to a refrigerant compressor (not shown). An expansion valve 94 controls the flow of the refrigerant fluid through the several heat exchanging shelves in such a manner that shelves 84 will be maintained at a desired temperature.

In order to secure the several panels in substantially air-tight relationship with each other and to prevent the transfer of heat from the outside to the inside of the enclosure, the several wall members have been provided with a special construction which will now be explained in detail.

The base member

As best shown in Figs. 10—16, base member 52 is formed of a thick layer of insulating material 100 which may be spun glass or some similar substance having a low thermal transfer capacity which is reinforced by a plurality of wooden cross-members 102 and a heavy metal channel supporting member 104 which extends about the ends of base member 52 in contact with insulating material 100. A pair of heavy channel beams 106 are located on the base member 52 for supporting member 52 in spaced relationship with the floor. Positioned above insulation material 100 and in contact with the upper surface of supports 102 and 104 is a layer of plywood 108. Positioned on the exterior surfaces of base member 52 is a continuous layer of thin metal 110. A similar layer of metal 112 is positioned on the upper or interior of the structure. Extending peripherally about the upper surface of member 52 with one surface in contact with plywood 108 is a rectangularly shaped beam of wood 114 which may be formed in four pieces and angularly joined at the corners of the structure as indicated by reference numeral 115 in Fig. 11. As clearly indicated in the several figures of the drawing, the exterior metal surface 110 is angularly bent about the outer edge of the wooden beam 114 and extends for only a short distance across the top of beam 114. Similarly the interior metal surface 112 is also angularly bent about the interior edge of wooden beam 114 so that a clear space of wood indicated by general reference numeral 116 is provided on the upper surface of wooden beam 114 which separates metallic surfaces 110 and 112. A continuous rubber gasket 118 having a circular bead is mounted on metal surface 110 adjacent the exterior side of wooden beam 114 to provide a sealing surface on the exterior of the structure and a similar gasket 120 is fastened to metal surface 112 adjacent the interior side of wooden beam 114 to provide a

sealing surface on the interior of the structure. Gaskets 118 and 120 are subject to a certain amount of stress and are therefore rigidly fastened by a plurality of fastening means. Alternately located on either side of beam 114 are a plurality of screws 122 which pass through gaskets 118 and 120, metal surfaces 110 and 112 and are threadedly secured in plywood 108. A plurality of fastening means 124 are alternately disposed on opposite sides of wood beam 114 for securing the outer metal surfaces 110 and 112 in immovable relationship to plywood layer 108 and insulating material 100.

As best shown in Figs. 17 and 18, fastening means indicated by general reference numeral 124 consists of an adapter 125 having a pair of nails 126 that pass through adapter 125 and enter the under surface of plywood 108. Adapter 125 is provided with a central threaded aperture 127 which is adapted to threadedly engage a bolt 128 that passes through metal surfaces 110 and 112, and plywood 108. A plurality of nails 130 are driven through the metal surfaces 110 and 112, wooden beam 114 and plywood 108 to rigidly secure the several members together.

By observing Fig. 10, it will be noted that a continuous surface of the nature just described extends about the upper surface of member 52 in such a manner as to form what is herein-after described as a tongued surface indicated by general reference numeral 134. It is of particular importance that tongued surface 134 has a central area 116 formed of wood or other low thermal transfer capacity material, which clearly separates the metallic surface 110 formed on the exterior of the member from the metallic surface 112 formed on the interior surface of the member, to thus prevent thermal transfer between the two metal surfaces.

Top member

Referring now to Figs. 19 and 20, is shown the lower or interior surface of the top wall member 80. As indicated in cross-section in Fig. 5, member 80 is provided with an interior mass of insulating material such as material 100 which is reinforced by a wooden cross-member 136. A layer of plywood 138 which is similar in all respects to plywood layer 108 of base member 52, is located about the outer periphery of the lower surface of insulating material 100. As shown in Figs. 5 and 20, a first narrow layer of wood 140 is fastened to the lower outer edge of plywood 138 and a second narrow layer of wood 142 is fastened to the lower inner edge of plywood 138 in such a manner that a groove indicated by general reference numeral 144 is formed between layers 140 and 142 with an exposed portion of plywood 138 forming the inner surface thereof. A sheet of metal 146 is positioned on the outer surface of wall member 80 and has its lateral edges bent around the surface of the outer layer of wood 140 and terminating adjacent the exterior surface of plywood 138. Another sheet of metal 148 is positioned on the inner surface of wall member 80 with its lateral edges bent around the surface of the inner layer of wood 142 and also terminating adjacent plywood surface 138. A plurality of fastening means 124 are applied for securing metal surfaces 146 and 148 to wood layers 140 and 142.

It will now be apparent that top wall member 80 is provided with a continuous peripheral grooved surface 144 whose inner surface, formed of exposed plywood 138 or any similar material

having a low thermal transfer capacity provides a surface which will prevent heat transfer between metal surfaces 146 and 148, and also a surface which is adapted to receive a tongued surface of another wall member, which may be formed similar to tongued surface 134 of base member 52.

Front panel

Referring now to Figs. 5 and 21-23, is shown the construction of the front panel or wall member 54. The panel has been constructed with four large openings 152 each of which is adapted to accommodate a door member 56. Wall member 54 has internally about its periphery four plywood strips 154 which are joined to each other adjacent their end portions. Extending vertically between the top and bottom plywood strips 154 are two spaced supports 156 formed of plywood. At the outer lateral edges of the panel and positioned between plywood strips 154 and 156 are a plurality of wood blocks 160 to which the stationary portions of hinges 58 are adapted to be secured. Extending between 25 obliquely positioned center supports 158 are a pair of wood blocks 162 to which the stationary portions of latching device 60 are adapted to be secured. Also extending laterally between each pair of supports 156 and 158 are a plurality of cross-members 164 formed of wood, which define the upper and lower supports of openings 152. Each of the four internal surfaces of openings 152 is covered with a layer of wood 166 to which a layer of Bakelite 168 is fastened so as to provide a surface which is impervious to moisture and which can be maintained in a sanitary condition.

In the area surrounding the several openings 152 is located a quantity of insulating material 40 100 which is covered on the outside surface by a layer of metal 170 and on the inside surface by a layer of metal 172, that are of similar character to metal layers 110, 112, and 146, 148. The metal layers 170 and 172 are joined at the top and the two lateral edges to a tongued surface indicated by general reference numeral 174 as shown in Fig. 22, in identically the same manner as metal layers 110, 112 are joined to tongued surface 134 as previously described in conjunction with base member 52. On either side of tongued surface 174, two rubber gaskets 175, 176 which are similar in character to gaskets 118, 120, extend continuously from the lower edge of one of the lateral sides over the top edge and down to the lower edge of the other lateral side. On its lower edge front panel 54 is formed into a grooved surface indicated by general reference numeral 178 as shown in Fig. 23, which surface is similar in character to grooved surface 144 of top panel member 80.

Door

As shown in Figs. 1, 5, 27 and 28, doors 56 are supported by hinges 58 on blocks 160 of front panel 54 to close the several openings 152. A latching mechanism indicated by general reference numeral 60 which will be described in detail hereinafter is provided to maintain the door in a substantially air-tight fastness with front panel 54 when the door is closed.

As best seen in Figs. 27 and 28, door 56 is constituted of a mass of insulation 100 which is enclosed on its four edges by a layer of wood 178. As indicated in Figs. 5 and 27 the upper surface 180 and the lateral surface 182 adjacent the

obliquely faced support 158 are bevelled. The purpose of a bevelled surface 180 is to provide moisture drainage and the purpose of bevelled surface 182 is so that the door 56 will have an oblique surface co-operating with the oblique surface provided by member 158. Joined to each other about the lateral portions of the outer surface of the door are four strips of plywood 184. Encasing the outer surface of the door and bent around the edges of plywood 184 is a metal surface 186. Encasing the inner surface of the door and bent around wooden surfaces 178 is another metal surface 188. Encircling the inner surface of plywood strips 184 is a layer of Bakelite 190 over which is mounted a continuous rubber gasket 192 having a beaded surface which is adapted to engage the outer metal surface 170 of front panel 54. Another layer of Bakelite 194 is positioned between gasket 192 and the wood surfaces 178.

Latching mechanism 60 consists of a member 61 fastened to door 56 by screws 62. A manually operable handle member 63 is pivotally mounted at 64 within member 61 and carries a pawl 65 that is adapted to engage a cleft portion 66 of stationary member 67 which is fastened to wood block 162 by screws 62 on front panel 54. Handle 63 also carries within member 61 a finger 68 that is adapted to move with relation to an aperture 69 in member 61. A pin or lock (not shown) is adapted to fit in aperture 69 to prevent movement of handle 63 so that door 56 may be locked in a closed position to prevent it being opened by unauthorized persons.

End panels

Referring now to Figs. 29-32, are shown the details of construction of the end walls or panels 76 and 78, both of which are identical in form. A mass of insulating material 100 is formed with a central supporting member 196. On the lateral edges of their inner surfaces panels 76 and 78 each carry two strips of plywood 198 to the edges of which are fastened narrow strips of wood 200 to form grooved surfaces indicated by general reference numeral 202 which are similar to grooved surface 144 of top member 80. On their top edges panels 76 and 78 each have a layer of plywood 204 on which is mounted a wood beam 206 to form a tongued surface indicated by general reference numeral 208. On their lower edges each of the panels 76 and 78 carry a layer of plywood 210, which, with the aid of wood strips 212 and 214, forms a grooved surface indicated by general reference numeral 216, that is an angular continuation of grooved surfaces 202 on the inside surfaces of the panels. A layer of metal 218 is mounted on exterior surface of each of the panels and another layer of metal 220 is mounted on the interior surface of the panels and secured thereto by fastening means. These metal layers are secured with relation to tongued surface 208 and grooved surfaces 202 and 216 in the same manner as previously described in connection with metal layers 110, 112, 146, 148. A pair of rubber gaskets 222 and 224 which are similar to gaskets 118 and 120 are secured to metal surfaces 218 and 220 on either side of tongued surface 208.

It will now be apparent that end panels 76 and 78 each have one tongued surface 208 on the top edge, a grooved surface 216 on the bottom edge and two grooved surfaces 202 on its interior face.

5 The back wall or panel member 74 is built in substantially the same dimensions as front panel 54. As seen in vertical cross-section in Fig. 5, a mass of insulating material 100 is supported by means (not shown) between layers of plywood 226 and 228. A wooden beam 230 extends from the lower side of one edge over the top and down to the lower edge of the other side of the panel in contact with plywood layer 226 to form a tongued surface indicated by general reference numeral 232. On its lower edge a pair of wooden strips 234 and 236 are joined to plywood layer 228 to form grooved surface indicated by general reference numeral 238. An exterior metal surface 240 and an interior metal surface 242 are placed over the panel and joined to tongued surface 232 and grooved surface 238 in the same manner as has been previously described. A pair of rubber gaskets 244 and 246 are secured to metal surfaces 240 and 242 on either side of tongued surfaces 232 and from the lower side of one lateral edge over the top and down to the lower edge of the opposite side.

Fastening means

As best seen in Figs. 6-9, are shown several views in which the several wall members are joined one to the other. Each of the several wall or panel members which is to form an exterior surface is provided with an aperture 250 that extends entirely through the panel including either the tongued or the grooved surface whichever form of joining means the particular panel is provided with. Positioned between the outer metal layer and the interior surface of the plywood and extending through insulating material 100 is a tubular member 252 which is flanged on each end and which is fastened to the plywood layer by screws 253 as shown in Fig. 32 so as to provide abutment on one end with the metal surface and on the other end with the interior surface of the plywood layer. The co-operating wall or panel member will also have an aperture 254 positioned in co-operating relationship with aperture 250. Positioned within insulating material 100 adjacent aperture 254 is a tubular construction indicated by the general reference numeral 256 and shown in detail in Figs. 24 and 25. Tubular structure 256 consists of a plate member 257 having a tubular extension 258 formed integral therewith which carries an interior thread on a thickened portion 259 and is pinched off as indicated by reference numeral 260. Fastening means 256 is fastened to the surface of the plywood layer by co-operating screws and nuts 261 with the tubular portion 258 extending into insulation 100. Bolt 82 having an exterior washer 262 passes through tubular member 252 into fastening means 256 where the bolt threadedly joins the threaded portion 259.

It will be particularly noted that at each joint of a tongued surface and a grooved surface that bolt 82 passes through the junction of the tongued and grooved surfaces in such a manner that it does not contact either the exterior or the interior metal wall member and that it cannot, therefore, aid in thermal transfer between the exterior and the interior walls of the enclosure. It will further be noted that at the junction of each tongued and grooved surface the junction is, for at least a substantial distance, a junction of wood, with plywood, which will preclude thermal transfer and also will prevent moisture from

penetrating into insulation material 100 at any point adjacent the junction.

Assembly

In assembling the structure indicated by the general reference numeral 50 as may best be seen in Fig. 5, base member 52 is moved to the desired position. Thereafter back panel 74 is secured on the rear edge of base member 52 with grooved surfaces 238 in contact with tongued surface 134 and by means of a bolt 82 shown in the upper portion of Fig. 4 the two members are secured together with the portion of outer metal surface 240 which has been joined around wooden strip 234 in contact with gasket 118 and the portion of metal surface 242 which has been joined around wooden strip 236 in contact with gasket 120. When these two members are joined, it will become apparent that the area 116 of tongued surface 134 co-operating with the plywood surface of grooved surface 238 will preclude thermal transfer between metal layers 240, 242 and 110, 112. Thereafter end panel 76 is mounted on base member 52 and joined to back wall member 74 and base member 52 as shown in Figs. 6-9 with grooved surface 216 in contact with tongued surface 134 and grooved surface 202 in contact with one of the lateral edges of tongued surface 232 on back panel member 74 and secured to base member 52 and back panel 74 by one bolt 82 passing through its lower edge and 2 bolts 82 passing through its lateral side as best shown in Fig. 32. Front panel 54 containing the assembled doors 56 is then fastened to the front side of base member 52 with its grooved surface 178 in contact with tongued surface 134 of base member 52 and one lateral edge of tongued surface 174 in contact with grooved surface 202 of end panel 76. Thereafter, the heat exchanging shelves 84 are slideably mounted on racks 85 between back panel 74 and front panel 54 and tubular connections 86 and 88 are connected to expansion valve 94 and to the plurality of heat exchanging shelves 84 and at their other ends tubular connections 86 and 88 are joined to nipples 90 and 92 that are in turn adapted to be connected to a refrigeration compressor (not shown). Thereafter end panel 78 is joined to base member 52 back panel 74 and front panel 54 in identically the same manner as end panel 76. Thereafter, top panel 80 is mounted on the assembly with its continuous grooved surface 144 in contact with tongued surface 208 of end panels 76 and 78 and tongued surfaces 232 and 174 of back panel 74 and front panel 54 with the several layers of metal being separated by rubber gaskets 222, 224, 244, 246, and 175, 176 so that thermal transfer cannot occur between the several metal surfaces and the several surfaces are joined substantially air-tight.

The principal advantage of my invention is in providing a refrigerator construction formed of a plurality of prefabricated elements which may be easily moved to the place of installation and readily assembled with one another in such a manner as to form a "knock-down" construction. Another advantage is in the construction of a plurality of metalclad wall members adapted to be rigidly joined to each other wherein the junction areas of each member are formed of material having a low thermal transfer capacity, to preclude heat transfer through the metalclad walls. A further advantage is in the construction of an enclosure formed of a plurality of walls each of which has independent interior and exterior metal surfaces arranged so that none of the

interior metal surfaces come into contact with the exterior metal surfaces to serve as a path for the conduction of heat between the exterior and the interior of the enclosure. A still further advantage is in the construction of a prefabricated enclosure which is substantially air-tight.

As it will be apparent to those skilled in the art, numerous changes may be made within the scope of the invention and therefore my invention is defined in the terms of the appended claims.

I claim:

1. A refrigerator assembly comprising in combination, a plurality of independent metal clad wall members having co-operating portions formed of material having a low thermal transfer capacity, means for insulatingly securing each of said wall members consecutively in engagement with another wall member in such a manner that they collectively form a sealed enclosure, a plurality of heat exchanging shelf members supported on said walls within said enclosure, and means carried by one of said wall members for connecting said heat exchanging shelf members with a source of fluid refrigerant, said several members each being constructed as an independent unitary element for knock-down assembly with the remainder of said members.

2. A refrigerator assembly comprising, a plurality of wall members, a tongued surface formed on one of said members, a grooved surface formed on another of said members cooperable with the tongued surface to form a junction between said members, one of said surfaces being formed of material having low thermal transfer capacity, fastening means passing through said members at the tongued and grooved surfaces for securing said members in rigid relationship with each other, and a resilient gasket carried by one of said members for engagement with the other member laterally adjacent said tongued and grooved surfaces in such a manner as to render the junction of said members substantially airtight when said fastening means is secured.

3. An insulated cabinet embodying, a bottom wall member, a top wall member and four independent lateral wall members adapted for consecutive junction one with another, and with the top and bottom members to form a sealed enclosure, each of said wall members being composed of a substantially rectangular block of insulating material, a narrow strip of relatively hard material having a low thermal transfer capacity secured on an outer surface of each wall to form a junction surface for connecting said one wall member to another wall member, a first metal layer positioned on the outer surface of each of said wall members with one of its edges extending partially over one side of said strip, a second metal layer positioned on the inner surface of each of said wall members with one of its edges extending partially over the opposite side of said strip and terminating at a laterally spaced distance from the edge of the first layer to provide a remnant area on one side of said strip between the opposing edges of said metal layers at the junction surface, and fastening means which pass through said wall members at the remnant areas of said strips for rigidly securing one wall member to another in such a manner as to minimize thermal transfer between the inner and outer layers at the junction areas.

4. In a refrigerator cabinet, a wall member formed of insulating material, a joining surface on said wall for uniting said one wall member to another wall member comprising a strip of rela-

11

tively hard material having a low thermal transfer capacity engaging said insulation material and extending linearly along an outer surface thereof, a pair of metallic layers superposed on opposite sides of said insulating material with one edge of each layer extending to said strip, the opposite edges of said two layers terminating in contact with one horizontal surface of said strip at spaced apart distances from each other in such a manner as to expose a portion of said strip between the layers to thereby form a remnant area of low thermal transfer capacity material on the joining surface, and fastening means for securing the edge of each metallic layer to said strip.

5. In a refrigerator cabinet, a wall member formed of insulating material, a strip of relatively hard material having a low thermal transfer capacity engaging said insulation material and extending linearly along an outer surface thereof, a tongued surface formed on the outer side of said strip and adapted to cooperate with a grooved surface on another member to form a junction between said members, a pair of metallic layers superposed on opposite sides of said insulating material with one edge of each layer extending to said strip, the opposite edges of said two layers terminating in contact with the outer surface of said strip at spaced apart distances from each other in such a manner as to expose a portion of said strip between the edges of said layers to thereby form a remnant area of low thermal transfer capacity material on the joining surface, and fastening means for securing the edges of the metallic layers to said strip.

6. In a refrigerator cabinet, a wall member formed of insulating material, a strip of relatively hard material having a low thermal transfer capacity engaging said insulating material and extending linearly along an outer surface thereof, said strip having two laterally separated portions on its outer surface to form a groove on the outer surface of said strip which is adapted to cooperate with a tongued surface or another wall member to form a junction between said wall members, a pair of metallic layers superposed on opposite sides on said insulating material with one edge of each layer extending to said strip, the opposite edges of said two layers terminating in contact with the outer surface of said strip at spaced apart distances from each other within the groove in such a manner as to expose a portion of said strip between the layers to thereby form a remnant area of low thermal transfer material along the grooved surface, and fastening means for securing the edges of said metallic layers to said strip.

7. In a refrigerator cabinet, in combination, a pair of wall members formed of insulating material, a tongued surface positioned on an outer surface of one of said members, a pair of metal layers positioned on opposite sides of said wall member with their opposing edges spaced from each other and in contact with laterally separated portions of the tongued surface, a second of said wall members having a grooved surface formed on one portion cooperable with the tongued surface on the first wall member to form a junction between said members, a pair of metallic layers positioned on opposite sides of said second member with their lateral edges spaced from each other and in contact with laterally separated portions of the grooved surface on said member, and fastening means passing

12

through said members at the tongued and grooved surfaces between the lateral edges of the metallic layers on each of said members whereby the fastening means is thermally independent of the metallic surfaces on each of said wall members.

5 8. In a refrigeration cabinet, a wall member formed of insulating material, a strip of relatively hard material having a low thermal transfer capacity extending continuously in a linear 10 manner along the outer surface of the insulating material, a pair of spaced apart members positioned on the outer face of one portion of said strip in such a manner as to form a grooved surface between said members, a single member 15 positioned on the central outer face of another portion of said strip in such a manner as to form a tongued surface, the tongued surface being disposed on a different portion of said strip than the grooved surface, and a pair of metallic layers 20 superposed on opposite sides of said insulating material with their edges terminating at spaced apart distances on the members forming the tongued and/or grooved surfaces on said strip to provide a remnant area of low thermal 25 transfer capacity along the center of said strip between said metallic layers.

9. A refrigerator cabinet, comprising a plurality of rectangular wall members, a linearly extending tongued surface formed on one face of 30 one of said members, another of said members having a linearly surface formed on one face cooperable with the tongued surface on the other member to form a linearly extending junction between said members, each of said surfaces being composed of material having a lower thermal transfer capacity, a pair of metallic layers disposed on opposite sides of each of said wall members with their outer edges extending respectively to the tongued and grooved surfaces 40 and terminating in the same plane at laterally spaced apart distances on one side of said surfaces to prevent thermal transfer from one layer to another through their opposing edges, a pair of resilient gaskets disposed on opposite sides of 45 the tongued surface on one of said members for contacting the other member on either side of the grooved surface to render the junction substantially air-tight, and fastening means passing through said members at the tongued and grooved surfaces for securing said members in rigid relationship with each other.

FREDERICK M. JONES.
